UNITED STATES PATENT OFFICE.

ISAAC ROY SHEPARD, OF RIVER JUNCTION, FLORIDA.

METAL SCREEN.

1,313,562.

Specification of Letters Patent.

Patented Aug. 19, 1919.

Application filed June 7, 1917. Serial No. 173,426.

To all whom it may concern:

Be it known that I, ISAAC ROY SHEPARD, a citizen of the United States, residing at River Junction, in the county of Gadsden 5 and State of Florida, have invented certain new and useful Improvements in Metal Screens; and I do hereby declare the following to be a full, clear, and exact description of the invention, such as will enable 10 others skilled in the art to which it appertains to make and use the same.

My invention relates to a new and novel indestructible all-metal screen for windows and doors, and has for one of its objects the 15 provision of a screen which is simple in construction, strong and durable, and economical in view of its lasting qualities.

Another object of this invention is to provide an indestructible all-metal casing to be 20 used in conjunction with the screen frame and provided with means to provide for the close interfitting of the screen frame therein to efficiently prevent the passage of insects and the like around the edges of the screen 25 frame.

Another object of this invention is to provide a screen and its frame and a casing for the screen frame which are exceedingly sanitary and which casing is so constructed as 30 to adapt the casing for ready attachment to window and door frames of varying dimensions.

Another object of this invention is the provision of novel means for operatively 35 hinging the screen frame within its casing whether the same be applied to a door or a window.

These and other objects and advantages will more fully appear as the nature of the 40 invention is more clearly understood from the following description taken in connection with the accompanying drawings wherein there is disclosed one embodiment of the invention, but which is susceptible to 45 numerous variations and modifications in the form, construction and arrangement of the parts thereof to meet the exigencies of the case without departing from the spirit of the invention or exceeding the scope of the 50 appended claims.

In the drawings:

Figure 1 is a front elevation of the screen frame and its casing when the same are employed for screening doors.

Fig. 2 is a vertical sectional view, on line 55 2-2 of Fig. 1, showing the detail construc-

tion of the lower portion of the screen and the threshold of the door.

Fig. 3 is a horizontal sectional view, on line 3-3 of Fig. 1, showing the further detail construction of the screen and its casing and the manner of mounting the casing upon the jambs or door posts.

Fig. 4 is a front elevation of the screen and screen frame and its casing when the 65 same are employed for screening windows.

Fig. 5 is a vertical sectional view, on line 5-5 of Fig. 4, showing the detail construction of the screen and the window sill member coacting therewith.

Referring to the drawings, wherein similar reference characters denote corresponding parts throughout the several views, and referring to Figs. 1, 2 and 3 of the drawings, 1 denotes one of the side posts of 70 the door frame and 2 the door sill, it being understood, of course, that while only one of the door posts of the door frame has been shown it is intended to include the entire door frame in illustrating the application of 75 the invention.

The casing for the screen frame consists of the side bars 3 and the top bar 4. The side bars 3 and the top bar 4 are formed of a strip of metal which is bent substantially 80 along its longitudinal medial line and the wings thus provided are folded upon each other and in close contact and thereby providing an inner member and an outer member, the outer member of the side bars 3 being 85 formed with the corrugation or hollow rounded bead 5 and interposed within the corrugation or hollow bead 5 and between the inner member of the side bars 3 are the reinforcing rods or bars 6. The top bar 4 of the casing is likewise provided with the 90 inner and outer members similar to the side bars 3 and has its outer member also provided with the corrugation or hollow bead 5 and within which is also a reinforcing rod 95 or bar 6. This constitutes the casing for the screen door frame and the side bars 3 and top bar 4 of the casing are suitably secured to the side posts and the top of the door frame through the medium of the securing 100 members 7 which may be nails, screws or other suitable securing means. The beads 5 provide seats for the marginal beads of the screen frame.

Designed to be mounted upon the casing 110 and within the corrugations or hollow beads 5 is the screen door frame which consists of

the side rails 8 the top rail 9 and the bottom rail 10 having their meeting ends suitably secured together. The side rails 8, the top rail 9 and the bottom rail 10 of the screen door frame are each formed of a strip of metal also bent along its longitudinal medial line but closely around the reinforcing rod or bar 11 which provides the screen door frame with the outer rounded edges or beads 12 and the wings thus provided are folded upon each other in close contact so that the rails of the screen door frame are also formed with inner and outer members, the outer members of the rails 8, 9 and 10 of the screen door frame being provided with the corrugations or hollow beads 13, similar to the corrugations or hollow beads 5 of the bars of the casing, and positioned within the corrugations or hollow beads 13 of the rails of the screen door frame and interposed between the inner and outer members thereof are the reinforcing rods or bars 14. There are, however, interposed between the inner edge portion of the inner members 25 of the respective rails of the screen door frame on the one hand and the inner edge portion of the outer members of the respective rails and the reinforcing rods 14 of the screen door frame on the other hand, the respective edges of the screen 15, and for binding the respective edges of the screen 15 between these members of the respective rails 8, 9 and 10 are the bolts 16 which project through the members of the rails 8, 9 and 10 and the respective edges of the screen 15, but rivets or other suitable securing members may be employed in lieu of the bolts 16, so that when the securing members 16 are firmly fastened through the inner 40 and outer members of the rails 8, 9 and 10 and the respective edges of the screen 15, the respective edges of the screen 15 will not only be efficiently secured between the members of these rails, but in addition thereto 45 the reinforcing rods 14 will so bind against the edges of the screen 15 as to draw and maintain the screen 15 taut within the screen door frame.

The bottom rail 10 of the door frame is 50 made somewhat wider than the top rail 9 and therefore the inner and outer members of the rail 10 are additionally secured together through the medium of the bolts or rivets 17 or any other suitable securing means. The top rail 9 and the bottom rail 10 are provided, in addition to the corrugations 18 somewhat wider than the corrugations 13 so as to overlap the adjacent portions of 55 the corrugations 13 at the meeting points of the responsive rails of the screen frame. To additionally reinforce the screen door the reinforcing bar 19 is provided and which is formed in a similar manner to that of the 60 rails of the screen door frame and is pro-

vided with the longitudinally extending corrugation 20 in which is seated a reinforcing rod or filler for adding strength to the reinforcing bar 19, the bar 19 being secured to the side rails 8 and the screen 15 by the 70 bolts or rivets 21, and adjacent the securing ends of the bar 19 are the transverse corrugations 22 for overlapping the corrugations 13 of the rails 8. The screen door is hingedly connected to the screen door frame through 75 the medium of the spring hinges 23 having one of their wings suitably secured to one of the side rails 8 of the screen door and their other wings suitably secured to the adjacent side bars 3 of the casing, the opposite 80 side rail of the door being provided with any suitable form of handle or knob 24. Upon the door sill 2 is suitably secured by the screws 25 the threshold plate 26, formed in the same manner that the rails of the screen 85 door are formed and provided with the corrugation 27 reinforced by the rod or filler 28. The threshold plate 26 is so positioned upon the door sill 2 and in alinement with the inner edges of the side bars of the casing that 90 when the door is in closed position the rounded edge 12 of the bottom rail 10 will abut against and snugly engage the corrugation 27 of the threshold plate 26.

In Figs. 4 and 5 is shown the adaptation 95 of the invention to a window, and in this instance the construction of the casing for the window screen frame as well as the screen frame itself are identical to the construction of the casing and the screen door frame shown in Figs. 1, 2 and 3, with the exception that when employing the invention as a window screen the casing and the window screen frame are made slightly 100 smaller and the casing is attached to the respective parts of the window frame, but when employing the invention as a window screen the top rail 9 of the window screen frame is secured to the top bar 4 of the casing through the medium of the hinges 29 in lieu of the hinges 23 shown in Fig. 1, and also the reinforcing bar 19 which is provided when employing the invention as a screen door is preferably omitted when employing the invention as a window screen. 115 However, in lieu of the threshold plate 26 which I provide for the door sill for the screen door to abut against, I employ, in this instance, the abutting plate 30 secured to the outer face of the window sill 31 by 120 the nails or screws 32, and while this plate is also formed of a strip of metal folded upon itself, the same is provided in its upper folded edge 33 with the reinforcing rod or filler 34, the upper portion of the abutting plate 30 being, however, bent inwardly 125 over the upper face of the window sill 31 and in a manner to position the reinforced edge 33 just rearwardly of the lower edge of the window screen frame, so that the 130

lower edge of the window screen frame will snugly engage the upper edge portion of the abutting plate 30 when in closed position, and to provide for the escape of any 5 rain water or the like which may lodge upon the window sill 31 there is provided in the abutting plate 30 a plurality of apertures 35.

From the foregoing it will be seen that I 10 am enabled to produce a screen device and a casing therefor which can be readily attached to door and window frames even though the dimensions of the frames vary to a certain degree and that the same is 15 thoroughly sanitary and insect proof, and again, that the parts of the screening device I preferably form of such metal as galvanized steel for barns and outbuildings, jappanned steel, aluminum or brass for residences and offices, but I preferably form 20 the wire netting of sixteen mesh copper bronze so that the screen door or screen window will not have to be renetted, and, therefore, it will be seen that the device is 25 practically indestructible and while the same is formed of materials somewhat more costly than wood the lasting qualities of the device renders the same practically costless.

Having described my invention, what I 30 claim as new and desire to secure by Letters Patent, is:

1. A screen construction embodying a

screen frame including a sheet metal plate doubled on a longitudinal line with the wings extending inwardly, the bend of the 35 plate having a rounded hollow bead, a rod in said bead, one wing of said plate having a corrugation near the edge thereof, a rod in said corrugation, a screen extending between the edges of said wings, and between 40 the second named rod and one wing, and means clamping said wings together and clamping said screen and rods therein.

2. A screen structure embodying a casing and screen frame each including a doubled 45 sheet metal plate, the edge portions of the frame plate extending inwardly, said frame plate having a hollow rounded bead at its bend, a rod in said bead, a screen extending between the edge portions of the frame 50 plate, means clamping the edge portions of the frame plate together to clamp the screen therein, the casing plate having a rounded bead forming a seat for the bead of the frame, and a rod in the bead of the casing 55 plate.

In testimony whereof I have signed my name to this specification in the presence of two subscribing witnesses.

I. ROY SHEPARD.
